US0D1111076S

(12) **United States Design Patent** (10) **Patent No.:** **US D1,111,076 S**
(45) **Date of Patent:** **** Feb. 3, 2026**

(54) **LENS FOR EYEGLASSES**(71) Applicant: **Essilor International**,
Charenton-le-Pont (FR)(72) Inventors: **Matthieu Guillot**, Charenton-le-Pont
(FR); **Bruno Fermigier**,
Charenton-le-Pont (FR); **Gilles Le
Saux**, Charenton-le-Pont (FR); **Marius
Peloux**, Charenton-le-Pont (FR); **Cyril
Guilloux**, Charenton-le-Pont (FR);
Björn Drobe, Singapore (SG)(73) Assignee: **Essilor International**,
Charenton-le-pont (FR)(**) Term: **15 Years**(21) Appl. No.: **29/917,423**(22) Filed: **Nov. 20, 2023****Related U.S. Application Data**

(63) Continuation of application No. 17/985,609, filed on Nov. 11, 2022, now Pat. No. 12,085,784, which is a continuation of application No. 16/976,662, filed as application No. PCT/EP2019/055216 on Mar. 1, 2019, now Pat. No. 11,567,344, application No. 29/917,423 is a continuation of application No. 16/976,595, filed as application No. PCT/EP2019/055222 on Mar. 1, 2019, now Pat. No. 12,158,637, application No. 29/917,423 is a continuation of application No. 16/976,632, filed as application No. PCT/EP2019/055222 on Mar. 1, 2019.
